M. O. BORBECK,
LEAD PENCIL,
APPLICATION FILED JULY 28, 1919.

Patented June 8, 1920.

UNITED STATES PATENT OFFICE.

MARTIN O. BORBECK, OF SIOUX CITY, IOWA.

LEAD-PENCIL.

1,342,416.

Specification of Letters Patent.

Patented June 8, 1920.

Application filed July 28, 1919. Serial No. 313,681.

To all whom it may concern:

Be it known that I, MARTIN O. BORBECK, a citizen of the United States, and residing at Sioux City, Woodbury county, State of Iowa, have invented certain new and useful Improvements in Lead-Pencils, of which the following is a specification.

The present invention relates to pencils and more particularly to the type having 10 means for feeding forward the lead.

The principal objects of the invention are to provide an improved pencil of this type having an efficient and easily operated lead feeding device, and further to provide a 15 chamber for storing a supply of pencil leads. Other objects and features of novelty will be apparent from the description taken in connection with the drawings in which:

Figure 1 is a longitudinal sectional elevation through a pencil constructed in accordance with the present invention;

Fig. 2 is a longitudinal sectional elevation of a portion of the pencil showing the feed lever in raised position;

Fig. 3 is a transverse sectional elevation taken substantially on the line 3—3 of Fig. 1;

Fig. 4 is a transverse sectional elevation substantially on the line 4—4 of Fig. 1;

Fig. 5 is a similar sectional view taken 30 substantially on the line 5—5 of Fig. 1; and

Fig. 6 is a partial longitudinal sectional elevation of a modified form of pencil.

Referring to the drawings, the form of pencil illustrated comprises a barrel 10 including the tip 11 screw threaded in one end and the cap 12 threaded in the opposite end and closing the barrel. The barrel is provided with a longitudinal passage for holding the lead. As shown for this purpose the tip 11 has a tube 13 which projects from its inner end and telescopes in a tube 14 supported at its opposite end in a recess 15 formed in the cap 12. A plunger is disposed in the tube 14 and consists of a portion 16 which extends into the passage in the tip 11 and bears against the end of the lead 17. The plunger 16 is also formed with serrations or teeth 18 for a purpose presently to be described. In the form shown these serrations or teeth extend around the plunger and their peripheries bear against the interior of the tube 14 thus guiding the plunger.

At its upper end the tube 14 is supported 55 by the cap 12 and at its other end by a liner 19 disposed between the tube and the interior

of the barrel. As shown in Figs. 1 and 4, this liner is cut away for a portion of its length thereby providing a chamber 20 for storing extra pencil leads. In a similar 60 manner, if desired, the chamber 21 formed between the tube 14 and the upper portion of the barrel may be utilized for storing extra leads.

The mechanism for feeding forward the 65 lead comprises a lever 22 pivoted at 23 preferably on the tube 14. This lever normally fits in an aperture 24 extending through the wall of the barrel and is adapted to be raised to the position illustrated in Fig. 2. A pawl 25 is pivoted at 26 to the lever 22 and the free end thereof is adapted to extend through an aperture 27 in the tube 14 to engage one of the teeth 18 of the plunger. Thus when the lever 22 is swung down from the position illustrated in Fig. 2 to the position illustrated in Fig. 1 the plunger will be advanced a slight amount and thus push forward the lead 17.

In the form just described the pencil lead 80 is advanced by swinging the lever downward. In Fig. 6 a modified arrangement is illustrated in which the lead is advanced by the upward movement of the lever. In this form of the invention the lever 22' is pivoted as at 23' to the tube 14 and carries a pawl 25' pivoted at 26'. The end of this pawl is formed with a hook 28 adapted to engage one of the teeth of the plunger, this hooked end extending through the aperture 85 27' in the tube 14. It will be seen when the lever 22' is raised the plunger will be advanced toward the right as viewed in Fig. 6 thus feeding forward the lead.

The normal positions of the parts are illustrated in Figs. 1 and 6. When it is desired to use the pencil the operating lever 22 or 90 22' is raised. In the form shown in Fig. 6 this raising movement through the pawl 25' will project the lead 17 a slight amount 95 from the end of the tip 11. The lever 22' is then returned to its nested position. In the form shown in Fig. 1 the raising movement does not in any way project the lead, but when the lever is swung from the position shown in Fig. 2 to that shown in Fig. 1, the plunger will be advanced in the direction to project the lead.

When it is desired to push the lead 17 back within the pencil, the operating lever 110 2 is raised to the position shown in Fig. 2 and then the pencil is turned around its

longitudinal axis through about 180° so that the lever is on the underside of the pencil. Then the pawl will fall by gravity against the lever whereupon the lead 17 may be 5 pressed back into its passage and thereafter the lever and pawl move to their nested positions as shown in Figs. 1 and 6. As previously stated the chambers 20 and 21 may be used for storing extra leads, access to 10 the chamber 20 being had by removing the tip 11 and to the chamber 21 by removing the cap 12.

Although two specific forms of the invention have been described in detail, it is to 15 be understood that the invention is not thus limited but includes modifications and changes which come within the scope of the appended claims.

Having thus described the invention what 20 is claimed as new and desired to be secured by Letters Patent is:

1. A device of the character described including in combination, a barrel having a longitudinally extending passage open at 25 one end of the barrel adapted to hold a pencil lead, a plunger having a portion fitting said passage adapted to bear at one end against said lead, said plunger having annular ratchet teeth, an operating member, 30 and a pawl carried by said member operative on said teeth whereby the plunger and lead are advanced a step by each actuation of said member.

2. A pencil of the character described including in combination, a barrel having a longitudinal passage open at one end adapted to hold a pencil lead, a plunger in said passage adapted to bear at one end against the lead, a lever carried by the pencil, and 40 a pawl pivoted on the lever, said plunger having teeth adapted to be engaged by the pawl to advance the plunger when the lever is moved in one direction.

3. A pencil of the character described including in combination, a barrel having a longitudinally disposed tube open at one 45 end of the barrel adapted to hold a pencil lead, said barrel having an aperture through its wall, a lever pivoted to the pencil and

normally disposed to close said aperture 50 with its outer surface flush with the outer surface of the barrel, a pawl pivoted on the lever and operable through an aperture in said tube to advance the lead when the lever is swung in one direction. 55

4. A pencil of the character described including in combination, a barrel having a longitudinally disposed tube open at one end of the barrel adapted to hold a pencil lead, said barrel having an aperture through 60 its wall, a lever pivoted to the pencil and normally disposed to close said aperture; a pawl pivoted on the lever and operable through an aperture in said tube, and a plunger fitted in said tube engaged by said 65 pawl to advance the same when the lever is swung in one direction.

5. A pencil of the character described including in combination, a barrel having a longitudinally disposed tube open at one 70 end of the barrel adapted to hold a pencil lead, said barrel having an aperture through its wall, a lever pivoted to the pencil and normally disposed to close said aperture, a pawl pivoted on the lever and operable 75 through an aperture in said tube, a plunger fitted in said tube having annular teeth engaged by said pawl when the lever is swung in one direction, thereby advancing the plunger in the tube. 80

6. A pencil of the character described including in combination, a barrel having a longitudinal passage open at one end adapted to hold a pencil lead, a plunger in said passage adapted at one end to bear against 85 the lead, said plunger formed with serrations, an aperture through the wall of said barrel, a lever pivoted at one end of said aperture and normally closing said aperture, a pawl pivoted on said lever adapted 90 to engage said serrations and advance the plunger when the lever is moved in one direction and to hold the plunger and lead against inward movement when the lever closes said aperture. 95

In testimony whereof I affix my signature.

MARTIN O. BORBECK.
